MOTOR-GRADER MACHINE OR THE LIKE

George W. Swisher, Jr., and Gordon L. Spivey, Oklahoma City, and Don W. Smith, Edmond, Okla., assignors to CMI Corp., Oklahoma City, Okla., a corporation of Oklahoma

Filed Jan. 9, 1969, Ser. No. 15,270

Term of patent 14 years

Int. Cl. D12—09

U.S. Cl. D14—3

Des. 218,739

PAGE 2

FIG. 1 is an elevation view of a first side of a motor-grader machine embodying the novel design;

FIG. 2 is an elevation view of the opposite side thereof;

FIG. 3 is a top plan view of the novel design;

FIG. 4 is an elevation view of one end of the design;

FIG. 5 is a bottom view of the machine design; and

FIG. 6 is an elevation view of the end opposite that of FIG. 4 of the novel design for motor-grader machine and the like.

The dominant features of our design reside in the portions shown in full lines.

We claim:

The ornamental design for a motor-grader machine or the like, as shown and described.
